UNITED STATES PATENT OFFICE

145,662

DESIGN FOR A MIRROR FRAME OR THE LIKE

Freda Diamond, New York, N. Y., assignor to Syracuse Ornamental Co., Syracuse, N. Y., a copartnership

Application August 23, 1945, Serial No. 121,585

Term of patent 7 years

(CL. D29—20)

To all whom it may concern:

Be it known that I, Freda Diamond, a citizen of the United States, residing in New York, in the county of New York and State of New York, have invented a new, original, and ornamental Design for a Mirror Frame or the like, of which the following is a specification, reference being had to the accompanying drawing, forming a part thereof.

Fig. 1 is a front view of a mirror frame or the like, showing my new design; and

Fig. 2 is a side perspective view.

I claim:

The ornamental design for a mirror frame or the like, substantially as shown.

FREDA DIAMOND.
